SEALED BAG FOR LIQUIDS

David Bellamy, Jr., Kenilworth, and Philip Gregory Ralston, Villa Park, Ill., assignors to Baxter Laboratories, Inc., Morton Grove, Ill., a corporation of Delaware

Filed Mar. 17, 1968, Ser. No. 16,257

Term of patent 14 years

Int. Cl. D24—02; D9—01

U.S. Cl. D83—1

FIG. 1

FIG. 2

FIG. 3

FIG. 1 is an elevational view of a sealed bag, showing our new design, certain access tubes to the bag being drawn in phantom lines.

FIG. 2 is an elevational view of the same sealed bag, rotated 90° about its longitudinal axis with respect to FIG. 1.

FIG. 3 is a plan view of the top of the same bag.

We claim:

The ornamental design for a sealed bag for liquids, substantially as shown in solid lines and described.
